UNITED STATES PATENT OFFICE.

GUSTAV A. FREI, OF SPRINGFIELD, MASSACHUSETTS.

MODE OF AND MEANS FOR RENEWING THE FILAMENTS OF ELECTRIC INCANDESCENT LAMPS.

SPECIFICATION forming part of Letters Patent No. 499,916, dated June 20, 1893.

Application filed November 14, 1892. Serial No. 451,925. (No model.)

To all whom it may concern:

Be it known that I, GUSTAV A. FREI, a citizen of the United States, residing at Springfield, in the county of Hampden and State of Massachusetts, have invented new and useful Improvements in the Mode of and Means for Renewing the Filaments of Electric Incandescent Lamps, of which the following is a specification.

This invention relates to a new mode of, and improved means for, uniting filaments to the leading-in wires of electric incandescent lamps the same particularly appertaining to the renewal or replacement in the lamps of the filaments which have been burned out or destroyed.

The invention, so far as it resides in the method, consists in encircling the end portions of the filaments by the end portions of metallic joint tubes, uniting the joint by immersing the parts in a hydrocarbon, as naphtha, and passing an electric current through the tubes and proximate filament extremities, raising these parts to incandescence and taking thereupon a uniting hydrocarbon deposit, opening the bulb of the lamp, insuring the removal of the old filament from the leading-in wires, placing the other end portions of the joint tubes to surround the extremities of the leading-in wires, then pinching the tubes and finally exhausting the air and closing the bulb.

The invention as concerned in and by the means will be hereinafter fully described and pointed out in the claims.

In the accompanying drawings the manner of and means for carrying out this invention are illustrated, in which—

Figure 1 is a perspective view of the device herein termed the temporary mount. Fig. 2 is a view of one of the joint tubes. Fig. 3 is a perspective view which illustrates the act of placing the joint-tubes in engagement upon the temporary mount, and Fig. 4 is a perspective view illustrating the next step, that is, the engagement of the filament with the mounted joint-tubes. Fig. 5 is in part a side, and in part a sectional, view of and through the temporary mount, the joint tubes and filament. Fig. 6 is a perspective view showing a modification in the form of the temporary mount. Fig. 7 is a plan view of the temporary mount, joint tubes and filament and the

short-circuiting clamp in combination with which said parts are temporarily placed. Fig. 8 is in part a side view and in part a sectional view showing the filament and tubes with the joint between them completed. Fig. 9 is a perspective view of the opened lamp and the filament and connected joint tubes shown as being connected with the leading-in wires.

The temporary mount, A, consists of a small piece or flat body, a, of non-conducting material, as vulcanized fiber, provided with two receivers for the joint tubes, B. The receivers may consist of pins, b, b, suitably connected with the body by being driven into it and projected from the edge thereof, as seen in Figs. 1, 3, 4 and 5,—with which pins the joint tubes may, by their end portions, have 70 encircling engagements,—or the receiver may consist of the sockets, b², b², as seen in Fig. 6, into which the joint tubes, as to portions of their lengths only, may have temporary supporting engagements. The mount also has 75 the handle-stem, d, projected from its edge opposite the receivers.

The metallic collars or tubes, B, B, are placed in engagement with the receivers of the temporary mount and the filaments f, then have 80 their ends inserted in the open ends of the tubes; and in practice it is often desirable to wedge them in with short pieces of carbonized substance such as that of which the filaments are composed. The temporary mount with 85 the supported joint tubes and filaments engaged therewith, as seen in Fig. 5, are now placed into a short circuiting device or clamp which is then immersed into a hydrocarbon and a current is run through the one tube or 90 a portion thereof and through the proximate portion of the filament extremity, thence across to the other filament extremity and through the portion of the tube in engagement therewith, as indicated by the arrows in 95 Fig. 7.

A clamp which is designed for advantageous use in carrying out this improvement is fully illustrated and described in an application for Letters Patent of the United States 100 filed by me simultaneously herewith, Serial No. 451,924. This clamp comprises a rest or table, m, on which a filament may be supported with the tube-engaged ends thereof

projected therebeyond, a clamp-bar, m^2 , for confining the filament firmly against a transverse electrical conducting bar, m^3 , a pair of insulated contact-pieces, n, n , arranged in a transverse line at a short distance from the aforesaid transverse conductor, m^3 , and electrical conductors, m^4 , leading to the one and from the other of said contact-pieces. The clamp is of such size and so formed that as the temporary mount, A, is laid thereupon the tubes and filaments may have the disposition seen in Fig. 7, the end portions of the tubes next to the edge of the mount body, a , lying outside of and in contact with the aforesaid contact-pieces, n, n , being firmly held by the clamping arms, o, o . The clamp-supporting body, m^5 , and the table-end are of non-conducting material such as vulcanized fiber or rubber, and the clamping-arms are suitably insulated from each other and so that they may form no circuits. The current, passed through the parts clamped as described and immersed in the hydrocarbon, raises the parts at the joint to incandescence they taking thereupon a cementing or uniting deposit of carbon, as indicated at x , in Figs. 8 and 9. The clamping-arms being suitably opened, the temporary mount is taken from the clamp, carrying with it the filament and tube jointed thereto, which parts are removed from the temporary mount, and, by suitable pinchers or other implement, are carried within the bulb of the electric lamp, as seen in Fig. 9, (which lamp as understood, has been opened, and from which the removal of the old filament has been insured;) and the end portions of the joint tubes, the farther from the connection therewith of the filament ends, are placed over the leading-in wires and engaged therewith by pinching them on.

In Fig. 9 a form of double pinchers is shown which may be advantageously employed to engage the tubes at both of the filament ends, but as the construction and mode of operation thereof are manifest upon an inspection of the drawings and as the device constitutes no part of this invention, and as also other devices for this purpose might be employed, a detailed description thereof will be unnecessary. The temporary mounts, as will have become manifest by the foregoing, are devices of great

utility and advantage in the renewal of the lamps by the mode herein described.

I claim—

1. The improvement in the method of renewing the filaments of electric incandescent lamps which consists in encircling the end portions of the filaments by the end portions of metallic tubes, uniting the joint by immersing the parts in hydrocarbon and passing an electric current through the tubes and proximate filament extremities raising these parts to incandescence and taking thereupon a uniting hydrocarbon deposit, opening the bulb of the lamp, insuring the removal of the old filament from the leading-in wires, placing the other ends of the aforesaid tubes to surround the extremities of the leading-in wires, then pinching the tubes and finally exhausting the air and closing the bulb. 70

2. The mount for the purpose herein set forth, comprising a body of insulating material provided with two receivers for the end portions of joint tubes, substantially as described. 75

3. The combination with a short circuiting device comprising a rest for the filament and a conductor adapted to be contacted on by the filament near both the ends thereof, and two insulated contact-pieces each having an electric conductor connected thereto of a temporary mount consisting of a non-conducting body having receivers for the joint tubes whereby when the mount is in the clamp the tubes may bear against said contact-pieces, substantially as and for the purposes set forth. 85

4. A temporary mount for the purpose herein set forth consisting of a body of non-conducting material with two receivers for the joint tubes and a handle-stem, substantially as described and for the purpose herein explained. 90

5. The temporary mount for the purpose herein set forth, consisting of a body of non-conducting material provided with the projecting pins, b, b , and the handle-stem, substantially as described. 95

GUSTAV A. FREI.
